UNITED STATES PATENT OFFICE.

FRANKLIN WOODS, OF PHILADELPHIA, PENNSYLVANIA, ASSIGNOR TO
ALVONI R. ALLEN, OF WYCKOFF, NEW JERSEY.

CORNER-STRIP FOR BUILDINGS.

SPECIFICATION forming part of Letters Patent No. 593,150, dated November 2, 1897.

Application filed November 20, 1896. Serial No. 612,896. (No model.)

To all whom it may concern:

Be it known that I, FRANKLIN WOODS, a citizen of the United States, residing in Philadelphia, Pennsylvania, have invented certain 5 Improvements in Corner-Strips for Buildings, of which the following is a specification.

The object of my invention is to manufacture a cheap and substantial corner-strip adapted to be secured to the two adjoining 10 walls of a building and to project from the corner, so as to protect the plaster, as fully described hereinafter.

In the accompanying drawings, Figure 1 is a perspective view illustrating a corner of a 15 wall, showing my improved corner-strip in position, the upper portion of the figure showing the plaster. Fig. 2 is a transverse sectional view of the walls, showing the corner-strip in position. Fig. 3 is a side view showing 20 the openings for the plaster. Fig. 4 is a plan view of the blank, showing a method of cutting. Fig. 5 is a view of the cut strip separated. Fig. 6 is a side view of one of the cut strips bent to the proper angle. Fig. 25 7 is a sectional view on the line 7 7, Fig. 6. Fig. 8 is a view looking in the direction of the arrow, Fig. 5. Figs. 9 and 10 are views of modifications of the invention.

Referring in the first instance to Figs. 4. 30 and 5, which illustrate the preferred method of making the strips, A is a strip of sheet metal, preferably galvanized iron. This strip I cut in two longitudinal sections on the scroll line x by suitable mechanism, so as to 35 produce two sections B B. (Shown in Fig. 5.) These sections each have projections or wings b b', which are bent to the proper angle, so that the strip can be adapted to a projecting corner. The projections or wings b of one 40 section when cut out form spaces c in the other section, so that there is no waste, as the metal of the entire strip is utilized; but I may increase the space between the wings when a light corner-strip is required.

45 The wings b of each strip alternate with the wings b', one set being preferably bent in one direction and the other set being bent in the opposite direction, as shown in Figs. 6, 7, and 8. If, for instance, the corner is a right- 50 angled corner, then the wings are bent at an angle of forty-five degrees to a line y drawn

through the projecting rib a of the strip, as shown in Fig. 7, so that the rib, when the corner-strip is applied to the partition or other wall, will project at the corner, as 55 shown in Fig. 1, so that the plasterer can work up to the strip at each side.

It will be noticed that the wings are separated by the spaces c. These spaces are formed in the present instance by the cutting out of the projections or wings of the adjoining strip, where two strips are made from one sheet, as described above and as shown in Figs. 4 and 5.

The wings or projections are preferably 65 bent on a line z, Fig. 6, which is some distance from the inner edge of the rib a and is in the present instance at the narrowest point or neck of the wing. By bending the wings at this point I form a series of openings when 70 the strip is applied to the wall, as in Figs. 1 and 3, through which the plaster extends, so that the plaster at the strip will be interlocked therewith, as clearly shown in Figs. 1, 2, and 3. This prevents the cracking and 75 spreading of the plaster at the point where it joins the strip.

I preferably puncture the projections or wings b b' for the reception of the securing-nails, although when the strip is made of 80 light material the wings may be punctured by the nails or by the lather when the strip is placed in position; but I prefer to make the strip of comparatively thick material, so that it will not buckle out of shape when being 85 applied, as it is important that the rib a of the strip should be perfectly straight.

The finished strip can be readily shipped, as one strip will interlock with another in packing, so that a quantity of the material 90 can be packed in a small compass and in such a manner that the strips will not be distorted in handling.

I preferably use galvanized iron, so that the 95 projecting edge will not mark or otherwise disfigure the plaster or paper if the room is papered after plastering.

While I prefer the form shown in Fig. 1, the cutting may be angular, as shown in Fig. 9, or the strips may be cut as shown in Fig. 10. 100

I claim as my invention—

1. As a new article of manufacture a cor-

ner-strip having a rib with wings projecting therefrom, one set of wings being bent to one side and the other set of wings being bent to the opposite side, said wings being so arranged as to form interlocking spaces for the plaster, substantially as described.

2. As a new article of manufacture, a corner-strip having a rib *a*, wings *b*, *b'* projecting therefrom at intervals, the wings *b* bent at an angle to the rib *a*, and the wings *b'* alternating with the wings *b* and bent at an opposite angle to the wings *b*, said wings being

bent at a point some distance from the rib so as to form interlocking spaces for the plaster in the projecting portion of the corner-strip, substantially as described.

In testimony whereof I have signed my name to this specification in the presence of two subscribing witnesses.

FRANKLIN WOODS.
